US00D952,973 S

(12) United States Design Patent (10) Patent No.: US D952,973 S
Payne et al. (45) Date of Patent: * May 24, 2022

(54) GUITAR CLEANING CLOTH

(71) Applicants: Peggy Murphy Payne, Queen Creek, AZ (US); Timothy Evander Payne, San Tan Valley, AZ (US)

(72) Inventors: Peggy Murphy Payne, Queen Creek, AZ (US); Timothy Evander Payne, San Tan Valley, AZ (US)

() Term: 15 Years

(21) Appl. No.: 29/693,901

(22) Filed: Jun. 5, 2019

Related U.S. Application Data

(63) Continuation-in-part of application No. 29/561,786, filed on Apr. 20, 2016, now Pat. No. Des. 858,919.
